John J. Kleschka
INVENTOR

BY *Victor J. Evans*

ATTORNEY

WITNESS:

John Donovan

UNITED STATES PATENT OFFICE.

JOHN J. KLESCHKA, OF WATERBURY, CONNECTICUT.

PEN.

Application filed July 25, 1924. Serial No. 728,216.

To all whom it may concern:

Be it known that I, JOHN J. KLESCHKA, a citizen of the United States, residing at Waterbury, in the county of New Haven and State of Connecticut, have invented new and useful Improvements in Pens, of which the following is a specification.

My present invention has reference to a fountain pen. My object is the provision in a pen of this character of revoluble means for imparting a longitudinal movement to a piston in the pen barrel to cause the filling of the pen or to eject the fluid therefrom should occasion require.

To the attainment of the foregoing and other objects which will present themselves as the nature of the invention is better understood, reference is to be had to the drawings which accompany and which form part of this application.

In the drawings:—

Figure 1 is an elevation of a pen in accordance with this invention.

Figure 2 is an enlarged elevation of the rear end portion of the pen with parts broken away and parts in section.

Figure 3 is a longitudinal sectional view through the rear portion of the pen barrel showing the plunger moved inwardly thereof.

Figure 4 is a similar sectional view but showing the plunger moved in an outward direction through the barrel.

Figure 5 is an end elevation of the traveler sleeve, the toggle lever system being removed therefrom.

The fountain pen 1 may be, and preferably is, of the usual construction. The barrel, however, being constructed in sections, and more strictly speaking there is a fixed cap 2 on the outer end of the barrel. Between the cap 2 and the barrel 3 there is arranged a nut 4, that is designed to have engagement with a hollow screw 5. The screw 5 has its bore provided with spaced arms 6, between which there is pivoted, as at 7, a pair of links of a toggle lever system 8. One of the end pair of links of the toggle lever system is pivotally secured, as at 7, between the ears of a lug 9 that is secured by means 10 to the outer face of the cap 2. The securing means 10 also bind between the

lug and the cap the closed end 11 of a tube 12. The tube 12 is arranged centrally in the barrel 10 and has its opened end embedded in an annular groove in the shoulered portion 13 of the said barrel.

Arranged in the tube 12 there is a plunger 14. On its inner face the plunger is provided with a bifurcated lug 15, and in the bifurcation of said lug the second end of the toggle lever system 8 is pivoted.

With my improvement it will be noted that the turning of the nut 4 will impart a longitudinal movement to the screw 5. The spaced elements 6 in the bore of the screw pass through elongated slots 16 in the tube 12 and the screw is permitted a movement equaling the length of the said slot. This movement is sufficient to compress the toggle lever system, as described in Figure 3 of the drawings, causing the plunger to suck ink into the tube 12. By reference to the said Figure 3 it will be noted that the plunger, in its innermost position, is disposed a considerable distance away from the slot 16 so that ink cannot pass through the said slots. By turning the nut 4 in an opposite direction the toggle lever system will be expanded bringing the plunger 14 to the position shown in Figure 4. When in such position surplus ink will be ejected from the pen and the plunger will be positioned to suck ink into the tube 12 upon the turning of the nut 4 in the reverse direction.

Having described the invention I claim:

1. A fountain pen having a plunger therein, expandible means connected with the plunger and revoluble means for expanding or contracting said expandible means.

2. A fountain pen having a plunger therein, a toggle lever system connected with the inner end of the plunger and with the outer end of the pen barrel, a slidale element connected with the toggle lever system and revoluble means for imparting motion to the slidale element for expanding or contracting the toggle lever system.

3. In a fountain pen having its outer end provided with a cap spaced from the barrel, a tubular member in the barrel fixed adjacent to the inner end thereof and likewise fixed to the cap, a plunger in the tubular

member, a toggle lever system connected to the plunger and to the outer end of the tubular member, said tubular member, adjacent to its said outer end, being slotted, a hollow screw surrounding the tubular member, elements extending from the bore thereof pivoted to two of the cross links of the toggle lever system and a nut arranged between the barrel and cap and engaging with the threads of the screw for the purpose set forth. In testimony whereof I affix my signature.

JOHN J. KLESCHKA.
